LIGHTING FIXTURE

Reuben B. Benjamin, Chicago, Ill., assignor to
Benjamin Electric Mfg. Company, Des Plaines,
Ill., a corporation of Illinois

Application February 16, 1931, Serial No. 515,933
Renewed August 5, 1933

8 Claims. (Cl. 240—11.3)

This invention relates to lighting fixtures and has special reference to floodlights.

More particularly, this invention relates to enclosed floodlights whereby a widely divergent beam is projected through a relatively small opening in such a manner as to illuminate large areas with substantially uniform intensity.

A desirable feature of the invention is the provision of a comparatively small, compact, lighting unit in which all direct rays are directed through a relatively small opening to provide a widely divergent beam, and all reflected rays are caused to converge and be directed through the opening to effect a widely divergent beam of reinforcing rays, the combined effect of all of the rays causing substantially uniform intensity over a large area.

A further object is to provide a fixture having a small opening in one side thereof through which is emitted a widely divergent beam of intersecting rays, and comprises a housing having a light source therein with a main reflector portion positioned about the rear of the light source and a second reflector portion having a diameter not substantially greater than that of the main reflector portion positioned forwardly thereof for reflecting substantially all the light rays which are not directly reflected by the main reflector portion or directly emitted out through the small opening and directing them back against the main reflector which latter reflects all the rays intercepted thereby out through the small opening, the use of the small opening being made possible by the combination of the two reflector portions.

The front reflector is so formed and positioned that the double-reflected rays which are first reflected by the front reflector and then again by the main reflector portion strengthen and reinforce the divergent beam of light at the outer portion of the beam so that the center of the beam does not have a high intensity which gradually diminishes towards the outer portion, but instead a fixture of this type gives forth a beam of comparatively uniform intensity and even distribution throughout. Such a construction is unusually efficient and is particularly suitable for lighting large areas with a substantially uniform intensity.

It is common practice in the construction of floodlights where a fairly wide angle of distribution is required, to use the same form of housing and reflector as is employed where a narrow beam is desired, such as in a spotlight or automobile headlight, and to spread the light

beam by means of a glass lens either by stippling or other deformation which serves to accomplish this purpose. In all such devices the front opening must be made with a diameter at least equal to the largest diameter of the reflector employed in order that the unit be efficient.

A floodlight embodying the present invention has many advantages over and accomplishes results not possible in the use of the ordinary floodlight. By employing two reflector portions, substantially all the light from the light source may be reflected through an aperture which may be made very small as compared with the usual or conventional type, while, at the same time, the diameter of the reflectors and the length of the fixture may be kept within a reasonable size.

As only a comparatively small light emitting opening is required, the lens or glass cover, therefore, may be made with a diameter substantially one-half as great as that of the lens, which would ordinarily be required, and this means substantially one-fourth the area and perhaps as little as one-sixth of the weight. Furthermore, the length of the seal between the lens and the casing is cut in half, the danger of breakage of the lens is materially lessened and the cost of and labor in mounting the lens is greatly reduced.

As a lens of a small size is employed, the fixture, particularly the seal between the lens and the casing, may be made more completely weather-proof. For this reason the floodlights are adapted for use around athletic fields, especially baseball and football fields where it is necessary to throw the light upward so as to illuminate the underside of the ball after it rises above the eye level.

This type of unit is also suitable as an explosion-proof fixture for use in hazardous locations, as such fixtures having only a small lens may be made to withstand great force and also be substantially gas tight.

Explosions are prevented not by absolutely keeping gas out of the enclosure but by making the fixture destruction-proof and of such a construction that if from any cause the gas within the enclosure ignites the hot products of combustion will escape so slowly from the fixture that they will become cooled below the danger point before reaching the outside of the casing and will not, therefore, ignite the gas in the surrounding atmosphere. As a small lens may withstand a much greater force than a comparatively larger lens, it is evident that a great advantage is derived in constructing an explosion-

proof fixture with a comparatively small opening in which the lens or glass front may be positioned and through which substantially all the light from the light source is projected.

5 It is also an object of the present invention to provide a fixture of the type hereinabove referred to which may be so constructed that it may be easily placed and supported in a position to direct the light therefrom in the most 10 efficient manner.

Further objects and advantages will be apparent from the following description when taken in connection with the accompanying drawings, in which latter:

15 Figure 1 is a front elevational view of an adjustable floodlight embodying the present invention.

Fig. 2 is a central vertical cross sectional view taken on the line 2—2 of Figure 1;

20 Fig. 3 is a central vertical cross sectional view of another form of floodlight embodying the present invention having a handle for carrying the same and legs or supporting members upon which the fixture rests or by which it may be 25 hung;

Fig. 4 is a side elevational view of the construction shown in Fig. 3 suspended from a wall;

Fig. 5 is a side elevational view similar to Fig. 4 showing the fixture resting on the floor;

30 Fig. 6 is a front elevational view of the fixture shown in Figs. 3, 4, and 5 with the axis of the reflectors in a horizontal position;

Fig. 7 is a central vertical cross sectional view of an explosion-proof fixture embodying the present invention; and

Fig. 8 is a central vertical cross sectional view of a ceiling fixture embodying the present invention.

Referring more particularly to the drawings, the construction shown comprises a two-part casing consisting of a rear portion 1 having a hood 2 extending therefrom and a front portion 3 pivotally secured to the rear portion 1. The front portion 3 is provided with a central opening 3a which is comparatively small as compared to the inside diameter of the casing. A socket 4 is secured in the hood and provided with the usual threaded shell portion 5 in which a lamp 6 is threaded to extend into the casing formed by the rear portion 1 and the front portion 3, the light source of said lamp being preferably no further forward than the front of the rear casing portion 1.

55 A main reflector portion 7 which is shown in Fig. 1 as being substantially spherical in form, but which may be parabolical, is positioned within the rear casing portion 1, being attached thereto by a screw 8 which threads into the casing portion 1, and having a peripheral flange portion 7a which fits into a peripheral notch 7b in the forward portion of the rear casing portion 1. An opening 9 is provided in the reflector through which the stem of the lamp 6 may be inserted for threading it into the socket 4. The lamp is preferably positioned so that when the lamp is inserted in the socket the junction of the neck and globular portion of the lamp lies close to the opening 9 in the reflector. The reflector 7 and lamp support are so designed that the position of the light source lies between the center or centers of curvature of the reflector and the focal points thereof so that the rays reflected by the reflector 7 intersect and pass through a small area a short distance in front of the cen-

tral portion of the reflector thereby forming a widely diverging beam of intersecting rays.

A front converging reflector portion 10 is mounted in the front casing portion 3 and is secured thereto by screws 11 which thread into the casing portion 3. This reflector portion 10 is substantially a continuation of the rear reflector portion 7, although in Fig. 1 the two are not shown as meeting. This is to allow for manufacturing variations. The front reflector portion 10 which is shaped so as to lie substantially adjacent the inner surface of the casing portion 3 is provided with two substantially spherical concentric reflecting surfaces 12 and 13. The radius of each is drawn with the light source of the lamp as a center or substantially thus, so that all the rays intercepted thereby are reflected back against the main reflector portion 7 from whence they converge and are projected outwardly in a widely diverging beam through the small opening 3a. The outer reflecting surface 12 lies adjacent the inner surface of the casing portion 3 and intercepts substantially all the rays which otherwise would strike the casing surface, while the reflecting surface 13 lies substantially within 25 and to the rear of the sides of the opening 3a and intercepts all the rays of the light projected forwardly of the reflecting surface 12 and not directly emitted through the opening 3a. With such an arrangement of reflectors substantially 30 all the light from the light source of the lamp is projected through the small opening 3a and this is accomplished while at the same time decreasing the diameter and the length of the casing and employing an opening small in comparison 35 to the diameter of the reflectors used.

As shown in the figures the globular portion of the lamp 6 extends substantially as far forward as the opening 3a in the casing and for this reason a spherical shaped front lens 14 is employed thereby allowing sufficient distance between the lamp and the lens without increasing the length of the casing. The lens 14 is provided with a flat peripheral ring 15, the front portion of which lies adjacent the inner front surface of the casing portion 3 where it is held by means of 40 spring clips 16 which are secured to the casing portion 3 by means of the screws 11. A packing 15a is positioned between the edge 15 of the glass front 14 and the front casing portion 3. 50

The two casing portions 1 and 3 are securely held together by means of eye bolts 17 and 18, the eye portions of the eye bolts 17 being pivotally mounted in the downwardly extending members 19 of the rear casing portion 1 about the 55 pivots 20. The threaded ends of the eye bolts extend forwardly through openings provided therefor in the ear portions 21 extending downwardly from the front casing portion 3 so that the front casing portion 3 may be pivoted forwardly about the pivots 20. Thumb nuts 22 are threaded on to the free end of the eye bolts 17 so that the casing portions may be tightly clamped together. The eye portion of the eye bolt 18 is pivotally mounted about the pivot 23 60 so that the free end, which extends forwardly through the slot 24 in the upper part 25 of the front casing 3, may be moved vertically in and out of the slot 24. A thumb nut 26 is threaded on to the end of the eye bolt 18 and engages 70 the sides of the slot 24 so as to tightly clamp the casing portions together. To pivot the front casing portion 3 away from the rear casing portion 1, the thumb nuts 22 and 26 are loosened. The eye bolt 18 is then swung upwardly out of 75

the slot 24 and the front casing portion 3 may then be pivoted about the pivots 20. In order to provide a tight seal between the casing portions, an annular ring 26a is inserted in the annular groove 26b in the front casing portion 3 which, when the two casing portions are tightly secured together, presses tightly against the rear casing portion 1 to form a tight seal.

The whole fixture is pivotally mounted on a stationary pipe or support 27 by the following means:

A Y shaped supporting member 28 is formed with a cup shaped stem 29 which is adapted to be placed over the end of an upright pipe 27. The stem 29 is formed with a longitudinal slot 30 which connects with the circumferential slot 31. Outwardly extending projecting members 32 are provided adjacent the sides of the slot 30 so that the stem portion may be tightly clamped about the pipe 27. A bolt 33 extends through openings provided therefor in the projecting portions 32 and a thumb nut 34 is threaded on the end of this bolt. By this means the Y shaped supporting member 28 may be rotated on the upper end of the pipe 27 and may be secured in any desirable position by tightening the thumb nut 34. The ends of the arms 35 of the Y shaped member 28 are adapted to fit over and against the ears 36 which are formed on the rear casing portion 1. Openings are provided in the ends of the arms 35, which openings register with openings in the ear portions 36. Bolts 37 extend horizontally through the openings in the ears 36 and the arms 35 so that the whole fixture may be vertically adjusted. Nuts 38 are threaded on to the ends of the bolts 37 which, when tightened, will hold the fixture in desired vertical position.

If desired, a guard 39 may be secured over the front glass or lens 14 and held in position by means of screws 40.

The constructions shown in the remainder of the figures are substantially the same as that described in connection with Figure 1. In Figs. 3, 4, 5 and 6, the front casing portion 3 is provided with a peripheral annular threaded portion 41 for threading into the inner threaded surface 42 provided on the forward portion of the rear casing 1 so that to secure the two casing portions 1 and 3, it is merely necessary to thread the front casing portion 3 into the rear portion 1. An annular portion 43 is provided on the periphery of the front casing portion 3 which engages the rear portion 1 and limits the distance the front portion may be threaded in the rear portion and also makes a tight fit between the two.

A handle 44 is secured to the apertured projecting members 45 provided on the top of the casing 1 and hood 2 whereby the fixture may be easily carried from place to place. Legs 46 are provided on the lower side of the casing portion 1 and an apertured leg or tail-piece 47 is secured to the lower side of the hood member 2 so that a three-point support is provided for the fixture. The legs and tail-piece are so formed that when the fixture is resting on the floor, as shown in Fig. 5, the beam of light from the fixture extends substantially between the vertical and the horizontal, the axis thereof extending upwardly about 45° from the horizontal.

Fig. 4 shows the fixture hung from a wall with the aperture in the tail-piece 47 placed over a support in the wall. When in this position the beam of light from the fixture is also substantially between the vertical and the horizontal but the axis of the beam extends about 45° down

from the horizontal. If it is desired to position the fixture so that the axis of the beam is horizontal, the fixture may be placed, as shown in Fig. 6. It has been found desirable in the forms of the fixture shown in Figs. 1 to 6, inclusive, to use a main reflector portion 7 which is substantially spherical, although, if desired, the same may be parabolical. In Fig. 3 an annular washer 48 is positioned between the bottom of the socket 4 and the inner end of the hood 2 to form a tight seal therebetween. With the construction shown in Fig. 3 in which the fixture is substantially air-tight except for the in-and-out breathing due to the change in temperature, the fixture may be used as an explosion-proof fixture.

The form of fixture shown in Fig. 7 is also very efficient as an explosion-proof fixture. In this form the main reflector portion 7 and the front reflector portion 11 are beaded together as shown at 49 to form a continuous reflector. The front reflector 11 is shown with only the one spherical reflecting surface 12, the second reflecting surface 13 being omitted. However, if desired, the front reflector may be provided with two reflecting surfaces, as shown in Figs. 1 to 6. In the device shown in Fig. 7, the main reflector portion 7 is shown as being substantially parabolical with the light source placed within the focal point of the parabola.

The front lens or glass 14, as in the device shown in Fig. 3, is made of heavy glass to withstand great shock. The lens 14 is mounted in the shield 50 by cementing, or any other desirable means for forming a tight fit therebetween, and the shield with the lens is threaded into the small opening in the front casing portion 3. The two parts of the casing are held together by screw bolts 51 which extend through apertures in the peripheral portion 52 of the front casing 3 and thread into the peripheral portion 53 of the rear casing portion 1. Thus a tight fit between the two casings is insured. A space 54 is left between the inner portion of the front reflector 11 and the front casing portion 3 to provide for ventilation so that the heat thrown off by the lamp 6 may escape through the opening 54 and be radiated off by the casing. This will prevent excessive heat within the reflectors.

As all the parts of the casing are tightly sealed together, in case an explosion occurs therein, the gases will be cooled below the danger point before they may escape into the atmosphere, thus preventing any danger of igniting the gases in the surrounding atmosphere.

A form of ceiling fixture embodying the present invention is shown in Fig. 8. In this form, no casing whatsoever is used. A hood 55 which is suspended from the ceiling is provided at the lower end thereof with a flange 56 and is secured to the main reflector 7 by means of screws 57 passing through the reflector 7 and the flange 56, on the end of which screws, nuts 58 are threaded.

The front reflector portion 11 is provided with a threaded flange 59 extending inwardly therefrom into which the lens 14 may be threaded. An annular diffusing glass member 60 is slid down over the hood 55 so that the lower end thereof engages the notches 61 in the main reflector 7. A slideable ring 62 is then slid down over the hood and over the upper end of the glass portion 60 which thereby forms a dust-proof protection about the jointure of the hood 55 and the main reflector 7. Apertures 63 are formed in the upper portion of the reflector 7

which is covered by the diffusing glass portion 60 through which light may escape upwardly through the diffusing glass portion 60 against the ceiling. Thus, there is formed a dust-proof, efficient, and inexpensive ceiling feature having a few parts and which may be easily assembled or taken apart.

While I have shown and described various embodiments of the present invention, it will be apparent to those skilled in the art that various modifications thereof may be made without departing from the spirit and scope of this invention, and therefore, I wish to be limited only by the prior art and the scope of the appended claims.

I claim:

1. A light projecting construction comprising a concave reflector, means for supporting an electric bulb with its light source between the center or centers of curvature and the focal points of the reflector whereby the reflected rays converge and cross each other, a zonal spherical reflector in front of said concave reflector having its center substantially at the light source whereby light from the zonal reflector will be reflected back onto the concave reflector and re-reflected as converging crossing rays, said zonal reflector having its rear edge adjacent the front edge of the concave reflector, and a protecting outwardly convex spherical glass cover in front of the bulb, said glass cover being substantially nearer the light source than is the zonal reflector, the outside diameter of said glass cover being materially less than the smaller diameter of the zonal reflector.
2. A light projecting construction comprising a concave reflector, means for supporting an electric bulb with its light source between the center or centers of curvature and the focal points of the reflector whereby the reflected rays converge and cross each other, a zonal spherical reflector in front of said concave reflector having its center substantially at the light source whereby light from the zonal reflector will be reflected back onto the concave reflector and re-reflected as converging crossing rays, said zonal reflector having its rear edge adjacent the front edge of the concave reflector, a protecting outwardly convex spherical glass cover in front of the bulb, said glass cover being substantially nearer the light source than is the zonal reflector, the outside diameter of said glass cover being materially less than the smaller diameter of the zonal reflector, and a two part casing for said reflectors separable substantially on the plane of junction of the concave reflector and zonal reflector, the rear housing portion being provided with a hood for housing the neck of the bulb and the bulb supporting means.
3. A light projecting construction comprising a concave reflector, means for supporting an electric bulb with its light source between the center or centers of curvature and the focal points of the reflector whereby the reflected rays converge and cross each other, a zonal spherical reflector in front of said concave reflector having its center substantially at the light source whereby light from the zonal reflector will be reflected back onto the concave reflector and re-reflected as converging crossing rays, said zonal reflector having its rear edge adjacent the front edge of the concave reflector, and a protecting outwardly convex spherical glass cover in front of the bulb, said glass cover being substantially nearer the light source than is the zonal reflector, the outside diameter of said glass cover being materially less than the smaller diameter of the zonal reflector, and a two part casing for said reflectors separable substantially on the plane of junction of the concave reflector and zonal reflector.
4. A light projecting construction comprising a concave reflector, means for supporting an electric bulb with its light source between the center or centers of curvature and the focal points of the reflector whereby the reflected rays converge and cross each other, a zonal spherical reflector in front of said concave reflector having its center substantially at the light source whereby light from the zonal reflector will be reflected back onto the concave reflector and re-reflected as converging crossing rays, said zonal reflector having its rear edge adjacent the front edge of the concave reflector, a protecting outwardly convex spherical glass cover in front of the bulb, said glass cover being substantially nearer the light source than is the zonal reflector, the outside diameter of said glass cover being materially less than the smaller diameter of the zonal reflector, said concave reflector having an opening in the rear for the passage of the neck of the bulb, and a hood for housing the neck of the bulb and the bulb supporting means.
5. A light projecting construction comprising a concave reflector, means for supporting an electric bulb with its light source between the center or centers of curvature and the focal points of the reflector whereby the reflected rays converge and cross each other, a zonal spherical reflector in front of said concave reflector having its center substantially at the light source whereby light from the zonal reflector will be reflected back onto the concave reflector and re-reflected as converging crossing rays, said zonal reflector having its rear edge adjacent the front edge of the concave reflector, a protecting outwardly convex spherical glass cover in front of the bulb, said glass cover being substantially nearer the light source than is the zonal reflector, the outside diameter of said glass cover being materially less than the smaller diameter of the zonal reflector, said concave reflector having an opening in the rear for the passage of the neck of the bulb, and a two part casing for said reflectors separable substantially on the plane of junction of the concave reflector and zonal reflector, the rear housing portion being provided with a hood for housing the neck of the bulb and the bulb supporting means.
6. An explosion-proof fixture comprising a casing capable of withstanding the internal pressure due to an explosion within said casing and sufficiently gas-tight so that the hot gaseous products, due to explosion, will be cooled in escaping sufficiently to prevent ignition outside of the casing, means for supporting a light source in said casing, said casing having a light aperture and a cover glass extending across said light aperture of sufficient diameter for the passage therethrough of a divergent cone of direct rays from the light source having an angle of at least thirty degrees at its apex forming a spreading beam outside of the casing, a rear concave reflecting surface for reflecting all light rays falling thereon in a convergent direction and through said light aperture forming a spreading beam outside of the casing having an angle of at least thirty degrees at its apex, and a front concave annular reflector surface for reflecting the light rays falling thereon from the light source onto the rear reflecting surface to be reflected in a convergent direction and through the light aperture, said light aperture being substantially smaller in diameter than the maximum diameter of the rear reflector surface.
7. An explosion-proof fixture comprising a

casing capable of withstanding the internal pressure due to an explosion within said casing and sufficiently gas-tight so that the hot gaseous products, due to explosion, will be cooled in escaping sufficiently to prevent ignition outside of the casing, means for supporting a light source in said casing, said casing having a light aperture and a cover glass extending across said light aperture of sufficient diameter for the passage therethrough of a divergent cone of direct rays from the light source having an angle of at least thirty degrees at its apex forming a spreading beam outside of the casing, a rear concave reflecting surface for reflecting all light rays falling thereon in a convergent direction and through said light aperture forming a spreading beam outside of the casing having an angle of at least thirty degrees at its apex, and a front concave annular reflector surface for reflecting the light rays falling thereon from the light source onto the rear reflecting surface to be re-reflected in a convergent direction and through the light aperture, said light aperture being substantially smaller in diameter than the maximum diameter of the rear reflector surface, the intersections of the converging rays from the rear reflecting surface lying within the space within said casing, thus preventing dangerously high temperatures outside of the casing.

30 8. An explosion-proof fixture comprising a

casing capable of withstanding the internal pressure due to an explosion within said casing and sufficiently gas-tight so that the hot gaseous products, due to explosion, will be cooled in escaping sufficiently to prevent ignition outside of the casing, means for supporting a light source in said casing, said casing having a light aperture and a cover glass extending across said light aperture of sufficient diameter for the passage therethrough of a divergent cone of direct rays 10 from the light source having an angle of at least thirty degrees at its apex forming a spreading beam outside of the casing, a rear concave reflecting surface for reflecting all light rays falling thereon in a convergent direction and through said light aperture forming a spreading beam outside of the casing having an angle of at least thirty degrees at its apex, and a front 15 concave annular reflector surface for reflecting the light rays falling thereon from the light source onto the rear reflecting surface to be re-reflected in a convergent direction and through the light aperture, said light aperture being substantially smaller in diameter than the maximum diameter of the rear reflector surface, said front 20 reflecting surface having a minimum diameter substantially smaller than the maximum diameter 25 of the rear reflector surface.

REUBEN B. BENJAMIN. 30
